UNITED STATES PATENT OFFICE.

FREDERIC HARRIS LEFTWICH, OF FLAT WOODS, TENNESSEE, ASSIGNOR OF ONE-THIRD TO THOMAS D. TATROM, OF LOVIC, TENNESSEE, AND ONE-THIRD TO GEORGE A. ARY, OF FLAT WOODS, TENNESSEE.

ROTARY ENGINE.

937,824.

Specification of Letters Patent. Patented Oct. 26, 1909.

Application filed May 6, 1909. Serial No. 494,262.

To all whom it may concern:

Be it known that I, FREDERIC HARRIS LEFTWICH, a citizen of the United States, residing at Flat Woods, in the county of Wayne 5 and State of Tennessee, have invented a new and useful Rotary Engine, of which the following is a specification.

This invention relates to rotary engines of that type having an annular steam chamber in which the head of a rotary piston travels, a sliding abutment being also provided which extends across the steam chamber and is periodically withdrawn therefrom to permit the piston head to pass.

15 It is the object of the present invention to provide a piston of novel structure, and also to provide improved means for operating the abutment.

20 The invention also has for its object to provide a novel arrangement of inlet and exhaust ports, together with a valve of great simplicity for controlling the inlet port.

25 A further object of the invention is to simplify the general structure of the engine, and to increase its efficiency.

With the foregoing objects in view the invention consists in a novel construction and arrangement of parts to be hereinafter described and claimed, reference being had 30 to the drawing hereto annexed in which—

Figure 1 is a transverse section of the engine. Fig. 2 is a section on the line 2—2 of Fig. 1.

Referring more particularly to the drawings, 5 denotes the cylinder of the engine, the same being provided with a suitable base 6 on which it is supported. Extending lengthwise through the cylinder is a shaft 7 provided with a fly-wheel 8 and a pulley 9. 10 The shaft 7 carries a pair of rotary pistons, each of which comprises a substantially semi-circular disk 10 formed with a hub 11 through which the shaft 7 passes. The piston is keyed or otherwise secured to the 15 shaft so as to turn therewith. At one end of the disk 10 is a follower head 12, and at the opposite end the periphery of the disk terminates in a cam 13. The bore of the cylinder 5 is suitably enlarged to receive 20 the hub 11, and the cylinder is also formed with circular recesses 14 in which the piston disks 10 travel, and these recesses are formed with annular steam chambers 15 in which the piston heads 12 travel. Between

the piston heads 12 and the cam 13, the 55 pistons carry a semi-circular rim or band 16 which is so located as to fit over the ends of the recesses 14 where they merge into the steam chambers 15, whereby that portion of the recesses 14 between the piston heads 60 and the cams is kept closed, and the entry of steam thereinto prevented.

At 17 is indicated the steam chest of the engine, steam being delivered thereto by a pipe 18. From this steam chest a port 19 65 extends to each of the chambers 15, and each of said ports is controlled by a valve 20 carried by one arm of a lever 21 which is pivotally mounted at 22 on a stud 23 in the valve chest. The other arm of the lever 70 21 is operatively connected to an abutment 24 working in an opening in the cylinder wall, and adapted to be extended radially across the steam chamber 15, and normally held in this position by means of a spring 75 25 mounted in the valve chest and pressing against that end of the lever to which the abutment is connected. Inasmuch as the valve 20 is carried by the other arm of the lever, it will be seen that when the abutment 80 85 is extended across the steam chamber 15, the valve 20 will be lifted off the port 19, and the latter is thus opened and steam is permitted to enter the steam chamber 15. The piston is moved out of the path of the 90 piston disk 10 and head 12, upon being engaged by the cam 13. When the abutment 20 is thus moved out of the way, the valve 20 closes the port 19 and shuts off the steam to the chamber 15.

At a point substantially diametrically opposite the inlet port 19, is an exhaust port 26 through which steam is exhausted from the chamber 15 when the piston head passes the same. Behind this exhaust port is located a radially sliding abutment 27 mounted in the walls of the cylinder 5, and held normally extended across the steam chamber 15 by means of a coiled spring 28. This abutment is pushed outwardly upon being 100 engaged by the cam 13, and thus moved out of the way of the approaching piston disk and head. When the head clears the abutment, the latter drops behind the same and prevents the steam from following the piston head after it passes the exhaust port.

Each of the rotary pistons is provided with the herein described valve mechanism

and abutments, and their operation is identical. The respective piston heads are located 180° apart in order to balance the engine.

5 The operation of the engine will be evident from the foregoing description, but it may be summarized as follows: Fig. 2 shows the abutment 24 extending across the steam chamber 15, and the piston head 12 in position about to uncover the inlet port 19. As soon as the piston head passes said port, steam enters the chamber 15 behind the piston head, and it is propelled in the direction of the arrow. When the cam 13 reaches the 10 abutment 27, the latter is pushed outwardly, and held in this position by the piston disk 10, the periphery of which fits snugly on the wall of the steam chamber. As soon as the piston head passes the abutment 27, the latter is pushed forwardly behind the same, and the exhaust through the port 26 takes place. When the cam 13 reaches the abutment 24, 15 said abutment is pushed out of the way of the approaching piston disk 10, and as soon as the latter passes the abutment, the abutment drops behind the piston head whereupon the parts are again in the position they occupied at the beginning of the herein-described cycle.

20 30 It will be seen from the foregoing that the engine is entirely automatic in its action, and all valve gearing is dispensed with, thus greatly simplifying the structure.

What is claimed is:

35 1. In a rotary engine, a cylinder having an annular steam chamber, and inlet and exhaust ports to said chamber, a rotary piston working in the steam chamber, and having a cam, a steam chest from which the inlet port 40 leads, a lever pivotally mounted in the steam chest, a valve controlling the inlet port, said valve being carried by an arm of the lever, and an abutment sliding across the aforesaid

steam chamber, said abutment being carried by the other arm of the lever.

2. In a rotary engine, a cylinder having an annular steam chamber, and inlet and exhaust ports to said chamber, an abutment and an inlet valve operated by the piston, and an abutment slideable across the steam chamber behind the exhaust port.

3. In a rotary engine, a cylinder having an annular steam chamber, and inlet and exhaust ports to said chamber, a rotary piston working in the steam chamber, said piston having a follower head and a cam, a steam chest from which the inlet port leads, a lever pivotally mounted in the steam chest, a valve controlling the inlet port, said valve being carried by one arm of the lever, an abutment slideable across the steam chamber, said abutment being carried by the other arm of the lever and operable by the aforesaid cam, and an abutment extending across the steam chamber behind the exhaust port, the last-mentioned abutment being operable by the cam to permit passage of the piston, and said abutment closing the steam chamber behind the piston, when the latter clears said abutment.

4. In a rotary engine, a cylinder having a circular recess, and an annular steam chamber communicating with said recess, a rotary piston, said piston comprising a semi-circular disk traveling in the aforesaid recess, and carrying a follower head, and a band extending between the ends of the disk, and fitting over the aforesaid recess to close the same to the steam chamber.

In testimony that I claim the foregoing as 80 my own, I have hereto affixed my signature in the presence of two witnesses.

FREDRIC HARRIS LEFTWICH.
